(57) **CLAIM**

The ornamental design for a heel for shoe, as shown and described.

DESCRIPTION

FIG. 1 is a perspective view of a heel for shoe showing our new design;

FIG. 2 is a left side elevation view of the heel for shoe shown in FIG. 1;

FIG. 3 is a right side elevation view of the heel for shoe shown in FIG. 1;

FIG. 4 is a bottom plan view of the heel for shoe shown in FIG. 1;

FIG. 5 is a front elevation view of the heel for shoe shown in FIG. 1; and,

FIG. 6 is a back elevation view of the heel for shoe shown in FIG. 1.

The broken lines showing a shoe are environment and form no part of the claimed design. The broken lines illustrating portions of the heel for shoe form no part of the claimed design.

1 Claim, 6 Drawing Sheets
